UNITED STATES PATENT OFFICE

ESTHER M. CARTER, OF NEWTONVILLE, MASSACHUSETTS

LIGHT-REFLECTING SIGNAL DEVICE

Application filed April 3, 1928. Serial No. 267,063.

My invention aims to provide means for giving visual signals, warnings, or other information by light reflection; while susceptible of widely varying uses, it finds particular application in use by pedestrians, bicyclists or others to give warning, to approaching vehicle-drivers, of the user's presence upon or near a highway.

In the drawings wherein I have shown certain illustrative embodiments of my invention,

Fig. 1 is a perspective view of a device embodying one form of my invention, the device being in this instance in the general form of 15 a military collar or abbreviated cape;

Fig. 2 is a detail section on the line 2—2 of Fig. 1;

Fig. 3 is a perspective view of a second illustrative embodiment of the invention, in this 20 instance in the general form of a belt or belt-like device;

Fig. 4 is a section in the line 4—4 of Fig. 3;

Fig. 5 shows a further illustrative embodiment of the invention, wherein the device is 25 supported by or forms a part of a garment.

Referring more particularly to the drawings, and first to Figs. 1 and 2, the device or safety signalling means there shown is adapted to encircle the wearer's neck. It is preferably a relatively light weight device and of a flexible nature, permitting it to be rolled or folded into a compact package for carriage in a pocket, hand bag, or otherwise, when not required for use. The illustrative device, as shown, comprises a base or main element 1 formed of suitable fabric or other flexible material, having a lustrous or light-reflecting finish or surface. For this purpose I preferably employ a "metal cloth", or imitation metal cloth commonly known as "metalline", or any fabric or other flexible material which is lustrous or capable of reflecting light, and preferably white, silver or steel in color. Said base or reflecting element desirably is given a protective, transparent covering 2, which may be a flexible transparent cellulosic sheet material such as a comparatively heavy "glassene" or other suitable material. It is preferably colored 50 or tinted, in accordance with the color most

appropriate as a signal or warning under the circumstances with which the device is to be used. For use by a pedestrian or bicyclist to warn an approaching vehicle, by reflection of the light therefrom, the color red, as a danger or warning, is generally employed.

Said base and outer members 1 and 2 respectively are placed flatwise against each other and secured, as by a suitable edging or peripheral binding 3, shown at the upper edge of the device of Figs. 1 and 2, or by hemming, as illustrated at the lower edge in said figures. The described device is preferably cut or otherwise disposed in its formation so as readily to assume a substantially circular form, in the general manner of a collar. Suitable means such as one or more buttons, or other fastener, as indicated at 4 may be provided for releasably securing together the two ends of the device, to retain it in position about the neck or upon the shoulders of the wearer. It will be understood that the described safety signal or warning device is particularly for use under conditions of diminished visibility, whether at night or during the day, and will reflect back to a vehicle driver light rays from the vehicle's own lamps, informing the driver of the presence of the signal carrier or wearer in or near his path.

In Figs. 3 and 4, I have illustrated another form of device also embodying my invention. The safety signal means in this instance is of a belt-like form comprising a reflective base member or strip 5, which may be similar in character to the element 1 of Figs. 1 and 2, and a transparent outer member or strip 6 having a character similar to that of the element 2 of Figs. 1 and 2. Said base and outer strips 5 and 6 are secured together as by stitching, hemming, or binding at their edges, as indicated at 7, 7. A buckle 8, or other releasable fastening means is provided to secure the device in position about the wearer's body.

In Fig. 5 a further embodiment of my invention is illustrated wherein a reflective or base element 9 and outer transparent element 10 are carried in superposed relation upon a garment 11 either permanently, as a portion

thereof, or detachably, said base and outer elements being secured together as by the stitching indicated at 12. As illustrated in Fig. 5 the device is provided with means whereby it may be attached to and removed from the garment, said means comprising the pairs of eyelets or the like 13, 13 through which pins 14, 14 or other fastening devices may be passed.

10 In some instances, and in connection with a device such as that of any of the illustrative embodiments of my invention I may dispense with an outer or transparent covering element, in which case the reflective or base element may be itself colored or tinted to afford by reflection a light signal of the desired color.

15 My invention is not limited to the particular embodiments thereof herein illustrated and described by way of example, its scope being set forth in the following claims.

I claim—

1. A device for affording warning to a vehicle-driver of the presence of a pedestrian, 20 bicyclist or other person in or near the path of the vehicle, said means comprising a light-reflecting flexible fabric base element, a flexible, overlying, transparent, protective, element, means securing said elements together, 25 and means for retaining the device in position upon the person to reflect back to an approaching vehicle-driver light rays therefrom as a visual warning signal.

2. A device for affording warning to a 30 vehicle-driver of the presence of a pedestrian, bicyclist or other person in or near the path of the vehicle, said means comprising an annular, flexible light-reflecting element, a covering for said annular element including a 35 coextensive flexible, transparent, colored member, and means for securing together the opposite ends of said device to retain it in position about the wearer's person.

3. A device for affording warning to a 40 vehicle-driver of the presence of a pedestrian, bicyclist or other person in or near the path of the vehicle, said means comprising an annular, flexible light-reflecting element of general collar-like form, a similarly formed 45 transparent, flexible and colored member overlying and secured to said annular element, and means to retain said device in position about the wearer's neck.

50 In testimony whereof, I have signed my name to this specification.

ESTHER M. CARTER.
